United States Patent Office.

JAMES C. MERRITT, OF NEW YORK, N. Y., ASSIGNOR TO HIMSELF AND OSCAR J. MERRITT, OF THE SAME PLACE.

Design No. 2,706, dated July 16, 1867.

DESIGN FOR EYELETS.

The Schedule referred to in these Letters Patent and making part of the same.

TO ALL WHOM IT MAY CONCERN:

Be it known that I, J. C. MERRITT, of the city, county, and State of New York, have invented a new and original Design for Eyelets; and that the following description, taken in connection with the accompanying drawing hereinafter referred to, forms a full and exact specification of the same, wherein I have set forth the nature and principles of my said improvements, by which my invention may be distinguished from all others of a similar class, together with such parts as I claim, and desire to have secured to me by Letters Patent.

This invention relates to a new and original design for an eyelet to be used in cloth, leather, rubber, or any suitable material; and it consists in having the eyelet made in oblong form, one part being circular and the other part composed of parallel sides, the space between which is considerably less in diameter than the circular part, and the parallel sides connected by a semicircular end.

In the accompanying drawing a side view of a portion of a garter is shown provided with eyelets of my improved design.

A represents the circular portion of the eyelet; B, the narrow portion, with parallel edges or sides *a a*, and a semicircular end, *b*, as shown clearly in the drawing. The circular portion of the eyelet is designed to be of sufficient capacity to admit of the button being passed through it, the eye of the button being drawn within the narrow part B so that when the eyelet is looped over, the button and circular portion of the eyelet will be fully exposed and have a very neat, chaste appearance.

Having thus described my invention, I claim as new, and desire to secure by Letters Patent—

The general configuration of the eyelet, as herein shown and described, to form a new and ornamental design for the same.

JAMES C. MERRITT.
